BURIAL VAULT HANDLE

John J. Jameson, Hillside, and George J. Kloppenburg,
Chicago, Ill., assignors to Wilbert W. Haase Co.,
Broadview, Ill., a corporation of Illinois

Application December 15, 1959, Serial No. 58,671

Term of patent 14 years

(Cl. D19—2)

FIG. 1

FIG. 2

FIG. 3

FIG. 4

Fig. 1 is a top plan view of a burial vault handle embodying our new design;

Fig. 2 is a front elevational view thereof.

Fig. 3 is a rear elevational view of the same; and

Fig. 4 is a fragmentary perspective view of an end portion thereof.

We claim:

The ornamental design for a burial vault handle, substantially as shown.
